Atty.

UNITED STATES PATENT OFFICE.

EARL F. PIERCE, OF CHICAGO, ILLINOIS, ASSIGNOR TO THE BASSICK MANUFACTURING COMPANY, OF CHICAGO, ILLINOIS, A CORPORATION OF DELAWARE.

LUBRICANT COMPRESSOR.

Application filed April 21, 1924. Serial No. 708,008.

To all whom it may concern:

Be it known that I, EARL F. PIERCE, a citizen of the United States, and resident of Chicago, in the county of Cook and State 5 of Illinois, have invented a certain new and useful Improvement in Lubricant Compressors, of which the following is a full, clear, concise, and exact description, reference being had to the accompanying drawings, 10 forming a part of this specification.

My invention relates to improvements in lubricant compressors, and is particularly concerned with the provision of a novel type of lubricant compressor for supplying lubricant under high pressure to bearings to be lubricated. My improved compressor is particularly designed, though not limited, to form a part of a lubricating system comprising a plurality of fittings, 15 one of which is secured to each of the bearings of the mechanism to be lubricated, and a compressor comprising means for placing the lubricant therein under high pressure, and having, in addition, means for making sealed contact with the various fittings so that lubricant under high pressure 20 can be forced thereinto.

The objects of my invention are:

First, to provide a compressor of the 25 character described, which is simple in construction, economical to manufacture, and easy to operate;

Second, to provide a compressor of the character described comprising a barrel, 30 or low pressure cylinder, for holding a supply of lubricant, and a high pressure cylinder communicating with the barrel, and means for discharging lubricant from the high pressure cylinder into the bearings under high pressure;

Third, to provide a lubricant compressor of the character described, including a flexible discharge conduit terminating in a member for making sealed connection with the various fittings, the high pressure cylinder being located between the barrel and the discharge conduit;

Fourth, to provide a compressor of the character described, in which the high pressure upon the lubricant is created by rotating the barrel, or low pressure cylinder, relatively to another portion of the compressor which is provided with a handle.

Other objects of my invention will appear 55 as this description progresses, reference be-

ing had to the accompanying drawings, in which—

Figure 1 is a central longitudinal section through my improved compressor, the discharge conduit and associated parts 60 thereof being shown in side elevation, and

Figure 2 is a view, partially in elevation and partially in section, showing one form of fitting which can be used as a part of a lubricating system embodying my invention. 65

Referring to the drawings, my improved compressor comprises a barrel, or low pressure cylinder 5 having the detachable cap 6. This cap is provided with an air vent 7 to permit access of air to the interior of the barrel 5. A rod 8 is secured to the cap 6 and extends inwardly therefrom. The inner end of this rod is reduced in section, 70 as shown at 8', and terminates in a head 9, the features of which will later be referred to. A piston P, comprising the face plate 10, cup leather 11, and the follower plate 12, all of which are held together by the sleeve 13, is slidably mounted upon the rod 8, and adapted to contact with the lubricant confined between the piston P and the 75 end closure 14 of the barrel.

The end closure 14 terminates in a tubular extension 15, to which is secured, by 80 means of a screw threaded connection 16, the sleeve, or high pressure cylinder 17.

A metal washer 18, and a fibre or felt washer 19, are clamped between the shoulder 20 on the sleeve 17 and the end of the 85 tubular extension 15. The washer 18 forms a valve seat for the valve 21, the stem 22 of which projects into the tubular extension 15 and terminates in the head 23. A spring 24, confined between this head and the washer 18, provides means for yieldingly holding the valve 21 in its closed position. A second plunger P' is reciprocably mounted in the high pressure cylinder 17. This piston comprises the washer or gasket 25, which is preferably made of leather, and the edge of which is preferably confined in a sheet metal ring 26. A cup leather 27 is positioned in the bore of the high pressure cylinder 17 immediately behind the gasket 25, and surrounds the outer end of the tubular displacing member 28. A beveled ring 29 also surrounds the displacing member 28. The inner end of the tubular member 28 is flanged over, as shown at 30, to 100 105 110

form a seat for the valve 31. This valve is yieldingly held against its seat by the tension spring 32, confined between the valve and the inturned flange 33 at the outer end of the tubular member 28.

The piston P', comprising the elements just described, is yieldingly held in its outermost position by a compression spring 34, confined between the ring 29 and the washer

10 18 The outer end of the high pressure cylinder 7 has a pair of oppositely disposed cam slots 35 formed therein for receiving the pins or projections 36 extending outwardly from opposite sides of the hollow 15 plunger 37. A cap 38 threaded onto the outer end of the sleeve 17 provides means for preventing the pins 36 from being completely withdrawn from the cam slots 35, the inturned flange 39 of this cap performing the functions just referred to.

A sleeve 40 is secured to the outer end of the plunger 37 and communicates therewith. This sleeve carries the handle 41, and also has a plug 42 threaded into one side thereof 25 for a purpose which will later be referred to.

The flexible discharge conduit 43 is secured to the sleeve 40 and placed in communication therewith by means of the hollow swivel coupling 44, the details of construction of which may be varied as desired, and which, for that reason, is not described in detail herein. The discharge conduit 43 terminates in a coupling member 45 of well-known construction, and comprises, among other things, the pair of oppositely disposed bayonet or cam slots 46, which are adapted to receive the ends 47 of the pin, which extends through the fitting 48. This fitting is here illustrated as 30 35 being attached to a bearing 49, which is to receive lubricant from the compressor just described.

The operation of my improved compressor is as follows:

45 Assuming that the space between the piston P and the closure 14 is filled with lubricant, the operator attaches the coupling member 45 to a fitting 48, and then, grasping the barrel 5 in one hand, and the handle

50 41 in the other hand, the operator oscillates the barrel 5 relatively to the handle 41, or the handle 41 relatively to the barrel 5, whichever may be most convenient. When the barrel 5 is turned in the proper direction to cause the plunger 37 to be drawn

55 into the high pressure cylinder by the action of the slots 35 and pins 36, the piston construction P' will be forced inwardly, and any lubricant confined in the high pressure

60 cylinder will be forced therefrom past the valve 31 and through the tubular member 28, the cup leather 27, gasket 25, into the hollow plunger 37. When the barrel 5 is rotated in the opposite direction, the piston

65 P' will move outwardly under the influence

of the spring 34, thereby tending to create a vacuum in the high pressure cylinder, and to draw lubricant from the barrel 5 past the valve 21 and into the high pressure cylinder. The charging of the high pressure cylinder from the barrel 5 is expedited and insured by the action of the piston P, the outer face of which is subjected to atmospheric pressure entering the barrel 5 through the vent 7.

70 By oscillating the barrel 5 and the handle 41 relatively to each other, as described above, successive charges of lubricant can be forced through the conduit 43, the coupling 45, and into the fitting 48, until a sufficient quantity of lubricant has been forced thereinto. The operator then detaches the coupling member 45 and attaches it to the next fitting to be lubricated, where he repeats the operations just described.

75 When the piston P has moved inwardly until it surrounds the reduced portion 8' of the rod 8, the operator can remove the piston P from the barrel 5 for the purpose of refilling the latter by simply unscrewing the cap 6 and pulling it away from the barrel 5. The head 9 on the end of the rod 8 engages the sleeve 13 and carries the piston P with it. Air passing between the sleeve 13 and the reduced portion 8' of the rod 80 relieves the vacuum which might otherwise be produced back of the piston P, and thus enables the latter easily to be withdrawn from the barrel 5.

85 90 If desired, the operator can reverse the positions of the plug 42 and the swivel 44 so that the latter will be in line with the handle 41. This may make it somewhat more easy to approach bearings in certain positions than it would be with the discharge conduit connected, as shown in the drawings.

95 100 While I have described the details of construction of the preferred embodiment of my invention, it is to be clearly understood that my invention is not limited to these details, but is capable of other modifications and adaptations within the scope of the appended claims.

105 Having thus described my invention, what I claim is:

110 1. A lubricant compressor comprising a barrel, a piston reciprocable in said barrel, a cylinder communicating with said barrel, and having a cam slot at its outer end, an outwardly opening check valve between said barrel and said cylinder, a piston reciprocable in said cylinder, a hollow plunger reciprocable in the outer end of said cylinder and having a projecting pin slidable in said cam slot, a handle secured to said plunger, and a discharge conduit secured to said hollow plunger and communicating therewith.

115 120 2. A lubricant compressor comprising a barrel, a cylinder communicating with said

- barrel and having a cam slot at its outer end, a valve between said barrel and said cylinder, a piston reciprocable in said cylinder, a hollow plunger reciprocable in the outer end of said cylinder and having a projecting pin slideable in said cam slot, a handle secured to said plunger, and a discharge conduit secured to said hollow plunger and communicating therewith.
- 10 3. A lubricant compressor comprising a barrel, a cylinder communicating with said barrel, a piston reciprocable in said cylinder, a hollow plunger reciprocable in the outer end of said cylinder, a cam connection between said plunger and said cylinder for reciprocating said plunger and cylinder relatively to each other when said plunger and cylinder are rotated relatively to each other, a handle secured to said plunger, and a discharge conduit communicating with said plunger.
- 15 4. A lubricant compressor comprising a
- barrel, a cylinder communicating therewith, a piston reciprocable in said barrel, a discharge conduit communicating with said cylinder, a plunger reciprocable in said cylinder, a handle secured to said plunger, and connections between said cylinder and said plunger for reciprocating said last mentioned elements relatively to each other when 25 said last mentioned elements are rotated relatively to each other.
5. A lubricant compressor comprising a barrel, a cylinder communicating therewith, a piston reciprocable in said barrel, a discharge conduit communicating with said cylinder, a plunger reciprocable in said cylinder, a handle secured to said plunger, and connections between said cylinder and said plunger for reciprocating said last mentioned elements relatively to each other. 35 40

In witness whereof, I hereunto subscribe my name this 16th day of April, 1924.

EARL F. PIERCE.
